UNITED STATES PATENT OFFICE.

WALTER E. KINGSFORD, OF WEATHERFORD, TEXAS.

ADJUSTABLE FOOTREST.

1,337,919.

Specification of Letters Patent. **Patented Apr. 20, 1920.**

Application filed November 18, 1919. Serial No. 338,899.

To all whom it may concern:

Be it known that I, WALTER E. KINGSFORD, a citizen of the United States, residing at Weatherford, in the county of Parker and 5 State of Texas, have invented new and useful Improvements in Adjustable Footrests, of which the following is a specification.

This invention comprehends the provision of an adjustable foot rest, the rest proper being mounted upon a base adapted to be secured to the floor or other suitable support in a manner whereby the rest can be quickly and easily adjusted to any desired position for the comfort of the user.

15 The nature and advantages of the invention will be better understood when the following detail description is taken in connection with the accompanying drawings, the invention residing in the construction, 20 combination and arrangement of parts as claimed.

In the drawing forming part of this specification like numerals of reference indicate similar parts in the several views and 25 wherein:—

Figure 1 is a front elevation of the rest constructed in accordance with my invention.

Fig. 2 is a sectional view taken on the line 30 2—2 of Fig. 1.

Fig. 3 is a side elevation showing different adjusted positions of the rest by dotted lines.

Fig. 4 is a detail view of the foot rest separated from the base.

Referring to the drawing in detail, the base upon which the foot rest is mounted, comprises spaced uprights 10 each carrying a foot or floor engaging element 11 which is 40 secured to the floor of the support by means of the foot elements 12. The spaced uprights 10 are connected together by means of a transverse shaft 14, the opposite end of which projects through the enlarged extremities 15 of the uprights. These extremities 15 are of circular outline and the periphery of each is notched at 17 for the purpose to be presently described.

The foot rest proper indicated at 18 is 50 mounted for rotation between the corresponding upper extremities of the arms 19, these arms being arranged in parallelism and having their opposite lower extremities mounted upon the shaft 14 in a manner

whereby the arms 19 together with the foot 55 rest can be swung to any desired angle for the comfort of the user. Suitable nuts 20 hold the arms 19 positioned upon the shaft 14. The inner side of each arm 19 is channeled as at 21, while pivoted within each 60 channel is a latch element 22 which projects beyond the lower end of the channel to engage in one of the notches 17 of the uprights 10. The upper extremity of each latch element is slightly spaced from the rear wall 65 of the channel and terminates to provide a finger engaging portion 23. Interposed between this extremity of the latch element and the rear wall of the channel, is a spring 24 which exerts a pressure against the latch 70 element to hold the latter positioned within the adjacent notch of the uprights 10. In practice, the base is fixed upon the floor or other support by means of the fastening elements 13. The latch elements are then 75 moved from within the notches 17, and the arms 19 together with the foot rest proper indicated at 18 swung to any desired angle with respect to the floor for the comfort of the user. When properly positioned, the 80 latch elements are released and the spring 24 functions to move the latch element into engagement with the adjacent notches thereby holding the foot rest fixed relatively to the base in its adjusted position.

85 While I have shown and described what I consider the preferred embodiment of the invention, I desire to have it understood that I do not limit myself to the details shown, inasmuch as such changes may be resorted to when desired as fall within the scope of what is claimed.

Having thus described my invention what I claim as new is:—

90 A device of the class described comprising spaced uprights, means for connecting said uprights, the upper ends of said uprights being notched, a pair of arms pivotally mounted upon said uprights, a foot rest 95 connecting said arms and supported thereby, each of said arms being channeled, and a spring pressed latch element pivoted within said channel and arranged to engage the said notches whereby the foot rest is held 100 fixed relative to the uprights in any adjusted position.

105 In testimony whereof I affix my signature.

WALTER E. KINGSFORD.
